In France October 22, 1935

11 Claims. (Cl. 110—29)

This invention relates to a heating apparatus particularly suitable for domestic use, but also applicable for the heating of large premises, workshops, public halls, etc.

5 This apparatus presents the following advantageous features:

1. It is capable of burning all solid fuels indiscriminately, without changing the construction necessitating the intervention of a skilled 10 workman. Moreover, the apparatus is readily adaptable to burning fuel oil, by merely attaching a special burner thereto and providing a protecting plate for closing the solid fuel receptacle.

15 The apparatus is especially adapted for burning fuels the combustion of which is ordinarily difficult or necessitates special arrangement, for instance fine fuel of any nature, coke and anthracite breeze, etc., as well as wood in all its 20 forms, including tree trunks cut according to dimensions consistent with those of the feed hopper.

2. The furnace is automatically fed, without intervention of mechanical means operated from 25 the exterior.

3. In its ordinary form of construction, it necessitates, only one charging in coal or coal dust every 24 hours.

4. Its operation does not necessitate the use 30 of fans.

5. It can be easily substituted for heating apparatus already installed without modification of the accessories associated with such apparatus.

6. This apparatus is readily adaptable to installations utilizing hot air, or hot water (steam or hot water). In the latter case, the air tubes are replaced by straight, curved or helical water tubes, or by water jackets concentrically arranged or arranged as baffles.

40 7. In the case of hot air heating, the apparatus avoids the frequent inconveniences of old hot air stoves in which a portion of the gases of the furnace succeeded in penetrating into the premises to be heated.

45 8. In an example of construction which will be described hereinafter, the heating apparatus comprises the combination of the following elements, some of which in themselves constitute particular objects of the invention:

50 1. A fuel feeding hopper, made of heat insulating material, or cooled by circulation of air and resting, in this case, on a crown by means of hollow arms.

55 2. A furnace containing superposed grates with central concentric openings.

3. A system of tubes, arranged in the space through which the hot gases pass when they issue from the furnace, this system supplying hot air to a heat chamber from which distributing conduits extend.

4. A cone controlling the admission of fuel and closing the hopper for maintenance purposes.

In the accompanying drawings:

Fig. 1 is a vertical sectional view of a furnace embodying the features of the present invention; 10

Fig. 2 is a transverse section taken approximately on the line A—B of Fig. 1;

Fig. 3 is a sectional view taken along the lines C—D—E—F—G—H of Fig. 1;

Fig. 4 is a plan view illustrating a system of 15 grates suitable for use in connection with the apparatus herein described;

Fig. 5 is a central longitudinal section through a modified type of furnace showing a modified form of the invention applied thereto; 20

Fig. 6 is a central sectional plan view of the furnace shown in Fig. 4;

Fig. 7 is a transverse sectional view taken approximately on the line 6—6 of Fig. 4, showing the construction of the furnace wall, the heating apparatus being removed therefrom; 25

Fig. 8 is a sectional plan view of a portion of one form of means for controlling the admission of air to the grates of the furnace;

Fig. 9 is a vertical section through a portion 30 of a grate illustrating its construction adapting it for application of the air-controlling means shown in Fig. 7;

Fig. 10 is a sectional view through a portion 35 of a grate assembly showing a modified form of air-controlling means individually operable for each grate section;

Fig. 11 is a view similar to Fig. 9, but showing the air-controlling means for all of the grate sections operable as a unit. 40

Referring to Figs. 1 to 3, it will be seen that the heating apparatus comprises a tubular feeding hopper which, most generally will be axially and vertically arranged; this hopper is designated by 1 and its wall will conveniently be made of refractory materials in order to avoid the distillation or heating up of the fuel it contains. The hopper will feed the furnace by gravity. Its capacity is sufficient for avoiding too frequent charging operations. 45

In the example illustrated in Fig. 1, the hopper 1 is provided with a double refractory wall 2—2 with internal circulation of atmospheric air. For that purpose, it is arranged on a hollow crown 3, also made of refractory material, which 55

- is provided with a number of hollow arms 3^a — 3^b , etc., four in number in the example under consideration. Through these arms (Figs. 1 and 3) the crown rests on a masonry or brickwork 4 surrounding the furnace and having channels 5 opening in said arms, so that in the annular space of the hopper can circulate atmospheric air entering, according to the direction indicated by arrows 1^1 , one or more intake ports 6 .
- 10 The cooling air, heated by coming in contact with the hopper, is evacuated, according to the directions indicated by the arrows 1^2 , through special conduits 30 (Figs. 1 and 2), distinct from that through which the combustion gases escape.
- 15 The hopper can be simply constituted by a cylindrical heat insulated element internally or externally provided with a steel plate having, at its lower part, a ledge by means of which it is fitted on the refractory portion. The hopper can also be cast in one piece and secured to the upper part of the apparatus by any suitable means. A plug 1^e is provided for closing the hopper after the same has been charged.

The grate of the furnace is constructed in such a manner that not only can it receive a large quantity of air laterally, as ordinary grates, but moreover so as to surround the fuel in ignition with a mass of air arriving from all directions. The grate is constituted by several superposed elements arranged in stepped relation, three in number being shown in the example illustrated in the drawing (Figs. 1 and 4).

These elements are in the shape of crowns, each of which comprises, on the one hand, an inner part made of bars 8 foreshortened so as to form between the ends of diametrically opposite bars a central cylindrical space 9 and, on the other hand, a peripheral ledge 10 connected to the said inner part by spokes 11 and resting in an annular groove of the masonry or brickwork 4 .

An operating handle 12 allows of imparting to each grate an angular displacement of suitable amplitude, for instance 45° , in order to clear the interstices of the element. The bars 8 will, preferably, be very close to each other. It will also be convenient to give to the elements of the grate a certain conicity and to bevel the inner ends 13 of the bars, as indicated in Fig. 4.

The heating of atmospheric air, in order to distribute it in the various premises to be heated by means of hot air vents, is effected in a series of tubes 14 arranged about the hopper (Figs. 1 and 2) in the space 15 through which pass the hot gases produced by the combustion in the furnace.

These tubes 14 open, at their upper ends, in a heat chamber 16 . The atmospheric air enters (arrows 1^3) a port 17 , and passes through the tubes 14 in which it is heated by calorific conduction and is admitted (arrows 1^4) into the heat chamber 16 , from which conduits 18 convey it (arrows 1^5) towards the various hot air vents (not shown).

The tubes 14 will be made of any suitable material having in particular the property of being impervious to the furnace gases at the temperature of the heating enclosure, that is to say at about $900^\circ C$.

The number and diameter of these tubes will be determined by calculation or experience according to the dimensions of the apparatus and the conditions of utilisation.

The tubes 14 , instead of being rectilinear, are preferably arcuate or incurved, as clearly shown in Fig. 1, to increase their heating surface, and

in order to permit such, the space 15 into which the hot gases from the furnace rise as indicated by the arrows 1^6 , is given the maximum width consistent with the dimensions of the apparatus and with the installation of the hopper and its cooperating elements.

Eventually, the tubes 14 will be secured in a metal framework against which will be erected the refractory portion of the apparatus, the whole being, in any case, constructed in such a manner that a rigorously fluid-tight joint is provided between the path followed by the heating air on the one hand, and the combustion gases on the other hand, the latter being finally evacuated through a conduit 15^a towards the chimney.

An important feature of the invention resides in the combination, with the installation above described, of a cone 19 having the double function of partially or completely closing the hopper during the working of the apparatus or during the maintenance operations (for instance the cleaning of the grates) and to control the admission of fuel to the furnace.

As illustrated in Fig. 1 of the drawings, this vertically movable cone occupies, during the working of the apparatus, a position which sufficiently uncovers the opening of the hopper in order that the grate should continuously receive the necessary quantity of fuel, the latter spreading over the grates and on the side wall of the cone.

The level at which this cone is held stationary allows therefore of controlling the consumption.

For closing the hopper, when the furnace is to be cleaned, the cone is lifted, for instance by acting on an operating lever 20 , or by pulling it by means of a cable, link or its equivalent, attached to a hook 21 , which constitutes the end element of a rod passing vertically through the cone and secured to the base of the cone, or of a cylinder 23 serving as a base for the latter.

The cylinder 23 is guided, for instance, by means of a collar 26 connected by spokes 21 to the masonry of the furnace, as shown in Fig. 1. This masonry is perforated with openings 28 , provided with dampers, shutters or their equivalents, and so distributed as to ensure uniform admission of atmospheric air to the furnace.

The cone can, at will, be removed from the furnace, for instance when wood is used as fuel.

In the forms of construction which will be described hereinafter are also to be found in particular the upper hopper serving to supply the furnace with fuel, as well as the device for controlling the admission of fuel and for closing the hopper.

The modifications in the apparatus from that described above mainly relate, on the one hand, to the means used for reheating the air adapted to be sent in the distributing conduits, and on the other hand, to the constitution of the grate, and, finally, to the arrangement of the hopper and of its distributing closing cone.

Referring to Figs. 5 to 7, it will be seen that 101 designates the supply hopper, 102 — 103 the cylindrical device for controlling the admission of fuel and closing the hopper, 104 the system of superposed grates, 105 the inlet to the furnace for the air ensuring the combustion, 106 the fresh air inlet to the heater, and 107 the outlet for the gases of the furnace.

In this example, the reheating of the air is obtained:

(a) By contact of fresh air with a first casing 75

108 completely surrounding the furnace and the base of the supply hopper on which it forms a fluid-tight joint. This casing 108, of refractory material, is, preferably, provided with ribs 5 109, in order to increase the surface of the calorific exchanges. These ribs are fitted on a steel sheet plate 110, or the like, which completely encircles the casing.

(b) In combination, or not, with the preceding 10 means, by contact of fresh air with the conduits 111 for the evacuation of the gases and smoke of the furnace. In the example illustrated, these conduits are three in number, they are connected to the terminal conduit 112, leading these gases 15 and smoke to the exterior. They can be increased as far as their number, length or diameter is concerned. These discharge conduits, internally lined, or not, with refractory materials, are also provided with ribs 113 on their entire peripheral 20 surface or on only a portion thereof.

(c) By providing a second casing 114 in the form of a refractory sheath enclosing the unit formed by the furnace and the gas discharge device.

25 By utilising, preferably simultaneously, these three means, the fresh air taken from the atmosphere and admitted into an inlet chamber 115, first enters (arrows f¹) a chamber 116, where it is heated by contact with the gas discharge conduits 111-112, then circulates around the casing of the furnace 108, between said casing and the outer casing 114 (arrows f²) Fig. 6. Being thus heated, the air is directed (arrows f³), by a conduit 117, towards the distributing chamber (not shown) and from the latter towards the distributing conduits leading to the various premises to be heated.

A second group of modifications concerns the grate.

30 In that respect, adjusting means are provided allowing control and variation of the quantity of air admitted to the furnace.

In this instance, the stepped grates 104-104^a-104^b (four in number in the example shown in the drawing) are encircled, by a system of bands or rings comprising, for each grate, a pair of rings 119^a-120^a, 119^b-120^b, etc. In each pair, one of the rings is fixed and the other is movable, 35 in contact with the fixed ring, either inside or outside the same. Each of said rings comprises solid portions and apertured portions 121, 121^a, etc., in such a manner that by imparting to the movable ring an angular displacement about its center, the degree of admission of air is caused to vary, and this air, in order to have access to the fuel resting on the grates, must pass through the opening formed by two apertured portions more or less partially in coincidence. It is obvious that the maximum admission is obtained, for 40 each grate, when the apertures in the pair of cooperating rings are in complete register.

The action of these rings allows of completely or partially preventing the access of air on to the fuel resting on the grates and, consequently, of obtaining a simple and efficient control of the calorific power supplied by the apparatus.

The admission of air to the grates can also 45 be controlled by shutters 142 (Fig. 10), pivoted at 143, and controlled by links 144, pivotally connected to said shutters at 145. These links, provided with handles 146, have notches or teeth 147 (Fig. 11) for holding them stationary in the chosen position. They allow, either of uncover-

ing, or of partially or completely closing the air inlet to the fuel.

For the individual control of the shutters 142, shown in Fig. 10, can be substituted a collective control (Fig. 11). All the shutters, or some of them only, may be pivoted, in this case, on a common link 148, to which is pivotally connected a second link 149 pivoted at 150 on a crank 151 which is rockable on a fixed pin 152, the operation of this jointed system being accomplished 50 by means of a single link 153 provided with a handle 154.

It will be noted, that in the form shown in Figs. 10 and 11 the side walls 155 of the ash pit are vertical instead of being of conical shape as in the 15 example illustrated in Figs. 5 and 7.

It is moreover advantageous, in order to ensure a combustion as complete as possible of the carbon monoxide contained in the hot gases generated in the furnace, to lead these gases to the 20 upper part of the combustion zone.

For that purpose, in the walls of the primary casing 108 of the furnace are provided conduits 124 having their lower orifice at the base of the furnace and opening at 125 near the base of the 25 supply hopper (Figs. 5 and 6).

Figs. 8 and 9 represent a horizontal half-section and a vertical diametrical half-section, respectively, showing a modification of the devices for controlling the admission of air to the grates. 30

Each of the latter (or some of them only) may be provided with a crown or flange 136 rigid with the lower face of the grate and in which is provided a series of apertures 137 which can be either completely covered, or uncovered by a series of shutters 138 pivoted about pins 139. 35

The operation of these shutters is effected through the medium of links 140, pivotally connected, on the one hand, to said shutters and, on the other hand, to a second crown 141 movable about the centre of the system of grates. 40

It will therefore be understood that by imparting to the movable crown 141 an angular displacement in the direction of the arrow f⁵, this causes the simultaneous opening of all the shutters, whilst a displacement in the reverse direction imparted to the movable crown closes the shutters. 45

The movable crown 141 will be actuated by suitable operating members.

It is to be understood that the hopper, the obturator for the latter and the grates may be modified as far as the shape and position are concerned without departing from the spirit and scope of the invention.

Finally, it is obvious that the heating apparatus 55 described above can be used not only for the production of hot air for heating premises or the like, but that it is also applicable to other uses; in particular, the calorific energy supplied by this apparatus can be used for heating boilers or the 60 like intended for the production of power: stationary and moving boilers, marine boilers, etc., in which case the characteristic elements of the invention: hopper, grates, various devices for controlling the admission of air and fuel are associated with a system of water tubes, water jackets, or their equivalents, in place of the air heating tubes described above.

What I claim as my invention and desire to 65 secure by Letters Patent is:

1. In a device of the kind described, a fuel-feeding hopper, a feed regulating cone at the delivery end of the hopper, means for varying the position of the cone with relation to the hopper, a grate consisting of vertically stepped portions 70 75

- concentric to the hopper and cone, said portions being in inwardly stepped relation from top to bottom of the grate, each of said steps being provided with air admission ports, means to supply air for passage laterally through the grate ports, means for controlling the admission of air at each grate member, each of said air controlling means comprising a pair of adjacent annular members surrounding the grate, one of said annular members being fixed and the other movable, and means to adjust the movable members.
2. In a device of the kind described, a fuel-feeding hopper, a feed regulating cone at the delivery end of the hopper, means for varying the position of the cone with relation to the hopper, a grate consisting of vertically stepped portions concentric to the hopper and cone, said portions being in inwardly stepped relation from top to bottom of the grate, each of said steps being provided with air admission ports, means to supply air for passage laterally through the grate ports, means for controlling passage of air through said ports comprising an annular plate for each step of the grate and having a series of peripherally spaced notches, said plates being rotatable to bring the notches into and out of registry with the said ports.
3. In a device of the kind described, a fuel-feeding hopper, a feed regulating cone at the delivery end of the hopper, means for varying the position of the cone with relation to the hopper, a grate consisting of vertically stepped portions concentric to the hopper and cone, said portions being in inwardly stepped relation from top to bottom of the grate, each of said steps being provided with air admission ports, means to supply air for passage laterally through the grate ports, a series of shutters hinged to said grate and movable to open and close said ports, and means to actuate said shutters.
4. In a device of the kind described, a fuel-feeding hopper, a feed regulating cone at the delivery end of the hopper, means for varying the position of the cone with relation to the hopper, a grate consisting of vertically stepped portions concentric to the hopper and cone, said portions being in inwardly stepped relation from top to bottom of the grate, each of said steps being provided with air admission ports, means to supply air for passage laterally through the grate ports, a series of shutters hinged to said grate and movable to open and close said ports, the shutters being connected in radial groups, and a series of operating means each connected to a group of said shutters.
5. In a device of the kind described, a fuel-feeding hopper, a feed regulating cone at the delivery end of the hopper, means for varying the position of the cone with relation to the hopper, a grate consisting of vertically stepped portions concentric to the hopper and cone, said portions being in inwardly stepped relation from top to bottom of the grate, each of said steps being provided with air admission ports, means to supply air for passage laterally through the grate ports, a series of shutters hinged to said grate and movable to open and close said ports, the shutters being connected circumferentially, and operating means connected to said shutters.
6. In a device of the kind described, a fuel-feeding hopper, a feed regulating cone at the delivery end of the hopper, means for varying the position of the cone with relation to the hopper, a grate consisting of vertically stepped portions concentric to the hopper and cone, said portions being in inwardly stepped relation from top to bottom of the grate, each of said steps being provided with air admission ports, means to supply air for passage laterally through the grate ports, a series of shutters hinged to said grate and movable to open and close said ports, the shutters being connected circumferentially, and operating means connected to said shutters.
7. In a heating furnace of the type described, a fixed vertically disposed fuel-feeding hopper having a discharge opening at its lower end, a vertically movable feed-regulating member disposed below the hopper and presenting thereto a section corresponding in size with the discharge opening of the hopper, said member having an upper continuous oblique surface, a grate having openings for the passage of air and comprising vertically stepped tiers, the level of the successive tiers descending towards the center of the furnace, means for admitting air for traversing the openings of the grate, means for vertically displacing the feed-regulating member with respect to the hopper and to the stepped grate and causing said member to engage the discharge opening of the hopper thereby to close the same.
8. In a heating furnace of the type described, a fixed vertically disposed fuel-feeding hopper having a discharge opening at its lower end, a vertically movable feed-regulating member disposed below the hopper and presenting thereto a section corresponding in size with the discharge opening of the hopper, said member having an upper continuous oblique surface, a grate having openings for the passage of air and comprising vertically stepped tiers, the level of the successive tiers descending towards the center of the furnace, means for regulating the admission of air laterally for traversing the openings of the grate, means for vertically displacing the feed-regulating member with respect to the hopper and to the stepped grate and causing said member to engage the discharge opening of the hopper thereby to close the same.
9. In a heating furnace of the type described, a fixed vertically disposed fuel-feeding hopper having a discharge opening at its lower end, a vertically movable feed-regulating member presenting thereto a section corresponding in size with the discharge opening of the hopper, said member having an upper continuous oblique surface and a lower guiding elongation, a grate having openings for the passage of air and comprising vertically stepped tiers, the level of the successive tiers descending towards the center of the furnace, means for admitting air for traversing the openings of the grate, means for vertically displacing the feed-regulating member with respect to the hopper and to the stepped grate and causing said member to engage the discharge opening of the hopper thereby to close the same, and guiding means in engagement with the elongation of the feed-regulating member for guiding the same during its vertical displacements.
10. In a heating furnace of the type described, a fixed vertically disposed fuel-feeding hopper having a discharge opening at its lower end, a vertically movable feed-regulating member presenting thereto a section corresponding in size with the discharge opening of the hopper, said member having an upper continuous oblique surface and a lower guiding elongation, a grate having openings for the passage of air and comprising vertically stepped tiers, the level of the successive tiers descending towards the center of the furnace, means for admitting air for traversing the openings of the grate, means for vertically displacing the feed-regulating member with respect to the hopper and to the stepped grate and causing said member to engage the discharge opening of the hopper thereby to close the same.

- ing vertically stepped tiers, the level of the successive tiers descending towards the center of the furnace, said grate having an opening through which the elongation of the feed-regulating member passes, means for admitting air for traversing the openings of the grate, means for vertically displacing the feed-regulating member with respect to the hopper and to the stepped grate and causing said member to engage the discharge opening of the hopper thereby to close the same.
11. In a heating furnace of the type described, a fixed vertically disposed fuel-feeding hopper having a discharge opening at its lower end, a vertically movable feed-regulating member dis-
- posed below the hopper and presenting thereto a section corresponding in size with the discharge opening of the hopper, said member having an upper continuous oblique surface, a vertically stepped grate having openings for admission of air and presenting vertical corrugations, means for introducing air for traversing the openings of the grate, means for vertically displacing the feed-regulating member with respect to the hopper and to the stepped grate and causing said member to engage the discharge opening of the hopper thereby to close the same. 10

PHILIPPE CHARLES LOUIS DEMARÇAY.
